US00D968115S

(12) **United States Design Patent** (10) Patent No.: **US D968,115 S**
Chen (45) Date of Patent: ** Nov. 1, 2022

(54) **CHAIR**

(71) Applicant: **Sophia & William Brands Co. LTD**, Nanjing (CN)

(72) Inventor: **Meidi Chen**, Nanjing (CN)

(73) Assignee: **SOPHIA & WILLIAM BRANDS CO. LTD**, Nanjing (CN)

(**) Term: **15 Years**

(21) Appl. No.: **29/797,263**

(22) Filed: **Jun. 29, 2021**

(30) **Foreign Application Priority Data**

Jun. 18, 2021 (CN) 202130377560.X

(51) **LOC (13) Cl.** **06-01**
